UNITED STATES PATENT OFFICE

HOWARD L. KRATZ, OF PHILADELPHIA, PENNSYLVANIA, ASSIGNOR TO JOHN WANA-MAKER PHILADELPHIA, OF PHILADELPHIA, PENNSYLVANIA, A CORPORATION OF PENNSYLVANIA

DESIGN FOR A GARMENT STAND

Application filed October 9, 1929. Serial No 32,986. Term of patent 14 years.

To all whom it may concern:

Be it known that I, HOWARD L. KRATZ, a citizen of the United States, residing in Philadelphia, Pennsylvania, have invented a certain new, original, and ornamental Design for a Garment Stand, of which the following is a specification, reference being had to the accompanying drawing, forming part thereof, in which—

Fig. 2, is a sectional view on the line 2—2,
Fig. 1; and

Fig. 3, is a sectional view on the line 3—3,
Fig. 1.

I claim:—

The ornamental design for a garment stand, substantially as shown.

HOWARD L. KRATZ.
